UNITED STATES PATENT OFFICE

2,071,146

FOOTWEAR

Eugene B. Ward, West Springfield, Mass.

Application October 25, 1935, Serial No. 46,757

4 Claims. (Cl. 36—71)

This invention relates to improvements in footwear and is directed more particularly to improvements in devices for use in connection with shoes and the like which are constructed and arranged to support a certain part or parts of the foot.

The principal objects of the invention are the provision of a supporting device for a part or parts of the foot which, according to the novel features of the invention, is movable by movements of the foot and shoe to support said part or parts of the foot in all natural positions thereof. The device of the invention is particularly adapted to support that part of the foot commonly known as the metatarsal arch in somewhat the same manner as the device shown in my co-pending application Serial No. 743,980, filed Sept. 14, 1934.

According to special features of the invention a support member is arranged and adapted to support the metatarsal arch of the foot when the shoe and foot are relatively flat as well as when the shoe is bent or flexed by the foot as is the case when walking. By reason of its novel construction the device of the invention has a member which is movable up and down so that when in a shoe and the sole is bent or flexed the said member is caused to follow that part of the foot which it supports for the supporting function. In its broad aspects the device supports that part of the foot either when the sole and heel are flat on the floor or when one is raised relative to the other so as to bend or flex the bottom part of the shoe. In other words, the support of the device of this invention is actuated for its supporting function by the bending or flexing of the sole of the shoe as the wearer bends the foot.

It is a particular object of the invention to provide a supporting device which automatically assumes a supporting position as the foot is flexed so as to bend the shoe. The device is adapted for use in connection with shoes of all types and sizes and its novel features consist in a general way of a supporting member or members arranged for relative movements brought about by the flexing or bending of the shoe as the wearer bends or flexes his foot.

It is a particular object of the invention to provide a construction which brings about elevating movements of a supporting part beginning at a point forwardly of the shank to raise and support the metatarsal arch of the foot adjacent a point back of the metatarsal head. The device is so arranged that it may be located in a shoe

beneath that part of the foot known as the metatarsal arch and by reason of its novel construction relieves the strain where the usual type of footwear causes much discomfort. The device is adapted to be made a part of a shoe during the manufacture thereof or it may be made as a device for inserting in an already manufactured shoe.

Various and numerous other novel features and advantages of the invention will be more fully hereinafter referred to in connection with the accompanying description of the invention in the form at present preferred, and it will be understood that various changes may be made in the form of the device of the invention without departing from the spirit and scope of the invention. In the drawing:

Fig. 1 is a side elevational view of a shoe having the device of the invention associated therewith, the shoe being represented by dot-dash lines; 20

Fig. 2 is a plan view of the device shown in Fig. 1;

Fig. 3 is a transverse sectional view on the line 3—3 of Fig. 2 through the support member to illustrate that the support member may be curved or arched for its supporting function; 25

Fig. 4 is a side elevational view similar to Fig. 1 showing a slightly modified form of the device of the invention;

Fig. 5 is a diagrammatic view showing the device of the invention with the parts in a certain relative position; and 30

Fig. 6 is a diagrammatic view showing the same parts in another position.

Referring now to the drawing in detail, the invention will be more fully described.

A shoe is represented at S by dot-dash lines in Fig. 1 which has the usual heel 2 and sole 4 extending from the front part rearwardly and being formed adjacent the heel to support the foot between the heel and forward portion. The shoe S is shown as it appears when the sole and heel are on the floor or ground as in standing. It may be here pointed out that when one is walking the heel 2 of the shoe is elevated when bending the foot which results in such bending or flexing of the shoe as is permitted by the relatively rigid shank common in shoe constructions.

The novel device of this invention may be associated with a shoe during its manufacture as between the inner and outer soles thereof, or if desired the invention may take the form of a device which is adapted to be inserted in a shoe after its manufacture adjacent the inner side of the outer sole, and in that case an inner member of some 55

relatively soft and flexible material may be disposed thereover.

The device of the invention includes a pair of base plate members 10 and 12 which are adjacent-
5 ly disposed and hinged together on adjacent sides as at 14 for relative swinging movements on the pivotal connection 14. The plate member 10 may be more or less V-shaped in cross section as shown and it is arranged so that it may be disposed adjacent the inside of the sole of the shoe as is
10 the plate member 12.

Also hinged to the plate member 10 as at 15 there is what may be called a supporting member 16 and on the plate member 12 there is provided
15 actuating means, which may take the form of a projection 18 and which is disposed below the sup-
porting member 16. This means 18 extends up-
wardly from the plate member 12 and is adapted
20 to be engaged by the support member 16. As the
parts 10 and 12 swing relative to one another from
the positions shown diagrammatically in Fig. 5
to the position shown in Fig. 6, the support mem-
ber 16 is elevated from member 12 or it swings
25 upwardly relative to member 12 as members 10
and 12 swing relative to one another.

The pivotal connections 14 and 15 together with
the projection are so arranged as to bring about
the desired movement of the supporting member
16 and of course may be arranged in various ways
30 to obtain various movements of the support 16.

With the device disposed in a shoe the members
10 and 12 are caused to swing relative to one an-
other by the flexing or bending of the shoe so
that the support 16 is swung or moved up and
35 down by this bending of the shoe. The support
16 is located so as to support the metatarsal arch
of the foot and as the foot and shoe are flexed or
bent, the supporting member is caused to follow
the foot and support the particular part at all
40 times.

The device may be secured to the shoe in vari-
ous ways and its shape may be modified to pro-
vide means for attachment. Openings 19 are
45 shown for illustrative purposes through which
fastening means may extend into the sole. The
means may be permanently secured to the device
and shoe during the manufacture thereof or when
the device is made as an accessory it may be
50 slipped into a shoe and fastened in position.

55 An inner sole 8 is represented in Fig. 1 which
may be of thin pliable material disposed to over-
lie the supporting device. Or when the device is
made as an accessory there may be a layer of
suitable material thereover to correspond to the
inner sole.

In the form of the invention shown in Fig. 4,
base plate members 20 and 22 similar to members
10 and 12 are hinged at 24 and a supporting mem-
ber 26, like the member 16, is hinged to member
60 20, as at 25. There is an actuating member 28,
such as a projection as shown, associated with
one of the plate members such as 22 on which the
member 26 rests.

Thus when the sole is flexed, the parts 20 and 22
65 are moved relative to one another so that the sup-
port 26 is elevated relative to the sole. The meta-
tarsal arch region of the foot is in this way sup-
ported in all natural positions of the foot.

While I have described the invention in great
70 detail and with respect to a preferred form there-
of, it is not desired to be limited thereto since
many changes and modifications may be made
therein without departing from the spirit and

scope of the invention. What it is desired to
claim and secure by Letters Patent of the United
States is:

1. The combination with a shoe having a flex-
ible sole of a device for supporting the metatarsal
5 arch region of the foot comprising, a pair of ad-
jacently disposed base plate members disposed
adjacent the sole of the shoe adjacent the meta-
tarsal arch-supporting part thereof and hingedly
10 connected together for swinging movements rela-
tive to one another as the sole of the shoe is
flexed, a support member hingedly connected to
one of said plate members, and an actuating mem-
ber associated with the other of said plate mem-
bers for acting on and swinging said support
15 member, all adapted and arranged whereby said
support member is swung upwardly and away
from said sole by said actuating member as said
plate members are swung relative to one another
by flexing of the sole of the shoe. 20

2. The combination with a shoe having a flex-
ible sole of a device for supporting the meta-
tarsal arch region of the foot comprising, a pair
25 of adjacently disposed base plate members dis-
posed adjacent the sole of the shoe adjacent the
metatarsal arch-supporting part thereof and
hingedly connected together for swinging move-
ments relative to one another as the sole of the
30 shoe is flexed, a support member hingedly con-
nected to one of said plate members, and a pro-
jection associated with the other of said plate
members for acting on and swinging said sup-
port member, all adapted and arranged whereby
35 said support member is swung upwardly and
away from said sole by said actuating member
as said plate members are swung relative to one
another by flexing of the sole of the shoe.

3. The combination in a device for supporting
the metatarsal arch of the foot of, a pair of ad-
jacently disposed base plate members adapted
40 to be disposed adjacent the sole of the shoe ad-
jacent the metatarsal arch-supporting part there-
of and hingedly connected together for swinging
movements relative to one another, a support
45 hingedly connected to one of said plate members,
and an actuating member associated with the
other of said plate members for acting on and
swinging said support member, all adapted and
arranged whereby said support member is swung
50 upwardly and away from the sole of the shoe by
said actuating member when said plate members
are disposed adjacent the sole of a shoe and are
swung relative to one another by flexing of the
sole of the shoe.

4. The combination in a device for supporting
the metatarsal arch of the foot of, a pair of ad-
jacently disposed base plate members adapted
55 to be disposed adjacent the sole of the shoe ad-
jacent the metatarsal arch-supporting part there-
of and hingedly connected together for swing-
60 ing movements relative to one another, a sup-
port hingedly connected to one of said plate mem-
bers, and a projection associated with the other
of said plate members for acting on and swinging
said support member, all adapted and arranged
65 whereby said support member is swung upward-
ly and away from the sole of the shoe by said
actuating member when said plate members are
disposed adjacent the sole of a shoe and are
70 swung relative to one another by flexing of the
sole of the shoe.
